STOCKING

Robert Friedrich, Jr., Sewell, N. J., assignor to L'Opera Hosiery Mill, Inc., Glassboro, N. J., a corporation of New Jersey

Application February 15, 1952, Serial No. 18,532

Term of patent 14 years

(Cl. D47—7)

To all whom it may concern:

Be it known that I, Robert Friedrich, Jr., a citizen of the United States, residing at Sewell, in the county of Gloucester and State of New Jersey, have invented a new, original, and ornamental Design for a Stocking, of which the following is a specification, reference being had to the accompanying drawing, forming part hereof.

Fig. 1 is a side elevational view of a stocking embodying my new design; Fig. 2 is a fragmentary rear elevational view of the stocking shown in Fig. 1; and Fig. 3 is a fragmentary, enlarged, side elevational view of the stocking shown in Fig. 1.

I claim:

The ornamental design for a stocking, as shown.
